UNITED STATES PATENT OFFICE

121,696

DESIGN FOR A HANDKERCHIEF OR SIMILAR ARTICLE

Robert L. Palmer, New York, N. Y., assignor to Cluett, Peabody & Co., Inc., Troy, N. Y., a corporation of New York

Application January 15, 1940, Serial No. 89,467

Term of patent 7 years

To all whom it may concern:

Be it known that I, Robert L. Palmer, a citizen of the United States of America, residing at New York city, in the county and State of New York, have invented a new, original, and ornamental Design for a Handkerchief or Similar Article, of which the following is a specification, reference being had to the accompanying drawing, forming a part thereof.

The figure is a plan view of a handkerchief showing my new design.

I claim:

The ornamental design for a handkerchief or similar article, substantially as shown.

ROBERT L. PALMER.
